STOCKING

Frank G. Weisbecker, Glenside, Pa.

Application August 24, 1949, Serial No. 4,682

Term of patent 14 years

(Cl. D47—7)

To all whom it may concern:

Be it known that I, Frank G. Weisbecker, a citizen of the United States, residing at Glenside, State of Pennsylvania, have invented a new, original, and ornamental Design for a Stocking, of which the following is a specification, reference being had to the accompanying drawing, forming a part hereof.

I claim:

The ornamental design for a stocking, as shown.
FRANK G. WEISBECKER.
